CAR FOR AMUSEMENT RIDE

William O. Thomas, 3005 W. 66 Highway,
Springfield, Mo.

Filed Oct. 11, 1962, Ser. No. 72,073

Term of patent 14 years

(Cl. D34—5)

Fig. 1

Fig. 2

Fig. 3

Fig. 4

Fig. 5

FIG. 1 is a perspective view of the car showing my new design.

FIG. 2 is a side elevational view of the car shown in FIG. 1.

FIG. 3 is a rear elevational view of the car shown in FIG. 1.

FIG. 4 is a front elevational view of the car shown in FIG. 1.

FIG. 5 is a top plan view of the car shown in FIG. 1.

The broken line showing of a guard rail in FIG. 1 is for illustrative purposes only.

I claim:

The ornamental design for a car for amusement ride, substantially as shown and described.
